UNITED STATES PATENT OFFICE

2,476,905

BREECH MECHANISM FOR FIREARMS

Claude Alfred Perry, Olton, Roger David Wackrow, Handsworth, Birmingham, and Arthur Sydney Urry, Shirley, England, assignors to The Birmingham Small Arms Company Limited, Small Heath, Birmingham, England, a British company

Application March 19, 1947, Serial No. 735,560
In Great Britain October 24, 1945

Section 1, Public Law 690, August 8, 1946
Patent expires October 24, 1965

7 Claims. (Cl. 42—35)

1

The present invention is concerned with improvements in or relating to firearms and is particularly, though by no means exclusively, concerned with small-bore firearms of the kind used for miniature target shooting at, for example, fun fairs.

Small-bore firearms as used at fun fairs are generally of the blow back type and an attendant inserts a plurality of cartridges in a tubular magazine in the butt end of the firearm. Such firearms must be robust and capable of standing up to mis-handling and ill-usage and particularly the action part of the firearm must be capable of being used more or less constantly over a period of hours.

It is an object of the invention to provide a novel and improved small-bore firearm which is robust and capable of being used continuously and satisfactorily over a period of hours.

According to the present invention, the breech mechanism of a firearm comprises a pivoted sector-shaped bifurcated breech block, a channel in said breech block formed by the limbs thereof and an arcuate web, and a sear member for holding the breech block in a retracted position against the action of a spring.

The breech block is pivotally mounted for oscillatory movement on a bottom plate, and has a groove formed in the periphery thereof to receive a projection on a sear also pivotally mounted on the bottom plate. A trip pawl is mounted on a trigger for contact with the sear to release the breech block to the action of a torsion spring so that a firing pin carried by the breech block will strike a cartridge in the firing chamber of the firearm. Cartridges are supplied to the firing chamber from a tubular magazine and pass through a feed tube the outlet end of which is situated adjacent the mouth of the firing chamber. The feed tube is a pivotally mounted member and as the breech block is oscillated forwardly by its spring it is arranged to contact the underside of the tube and cam its forward end upwardly out of the way of the firing pin to allow the latter to strike the rim of a cartridge in the firing chamber.

In order that the nature of the present invention may become more clear a firearm illustrative thereof will now be more fully described with reference to the accompanying drawings, though it is to be understood that this has been selected for description merely by way of exemplification of the invention and not by way of limitation thereof.

2

In the said drawings:

Figure 1 is a left hand side elevation of the mid-portion of the illustrative firearm;

Figure 2 is a right hand cross-sectional view of the parts shown in Figure 1;

Figure 3 is a view illustrating the position of various parts during cocking of the firearm;

Figure 4 is a view similar to Figure 3 but showing the parts in an uncocked position;

Figure 5 is a rear end elevation of a breech block of the illustrative firearm;

Figure 6 is a section taken along the line VI—VI of Figure 5;

Figure 7 is a front end view of the breech block showing particularly a firing pin carried thereby.

Figure 8 is a view similar to Figure 2 but showing the parts in the positions which they occupy at the instant of firing;

Figure 9 is a vertical transverse section on the line 9—9 in Figure 8 but showing the parts in cocked position; and

Figure 10 is a view similar to Figure 9 but showing the positions of the parts at the instant of firing.

25 The illustrative firearm comprises a bottom plate 1 adapted to be secured to the body 3 of the firearm, the plate being generally U-shaped in cross-section. Pivoted at 5 to the forward end of the bottom plate 1 is the front end of a combined cocking handle and trigger guard 7. Pivoted upon the pivot pin 5 is a breech block 9 which comprises a sector-shaped member. The member is bifurcated, as is shown in Figure 5, and the two limbs are united by an arcuate cross web 11 which extends from the rear face of the member for a slight distance forwardly of the same, the space between the limbs and the inner wall of the web being adapted to form a channel for the passage of cartridge cases ejected from the breech chamber of the firearm.

30 At the lower rear corners of the limbs of the breech block 9 are formed ears 13 (Figure 6) through which the pivot pin 5 passes and a torsion spring 15 coiled round the pivot pin tends 45 normally to urge the breech block in a forward direction about the pivot 5. The periphery of the breech block 9 is provided with a notch 17 on its rear face to co-operate with a projection or tooth 19 formed on the front face of a sear member 21 hereinafter to be described. Pivoted to the breech block 9 and extending along the underface of the web 11 is a cartridge extractor 23 which comprises a hooked forward end 25 (Figure 6). A torsion spring 21 surrounds the pivot

50 of the extractor 23 and normally urges the hook-55

shaped end upwardly. Adjacent the forward end face of the web one of the limbs is drilled to provide accommodation for a laterally extending firing pin 29 (Figure 7) that stands proud of the web and is situated above the hook-shaped end of the extractor 23. The arrangement of the extractor 23 and pin 29 is such that as the breech block 9 is rocked forwardly by its torsion spring 15 the pin 29 will strike the base of a cartridge in the firing chamber of the firearm and the end 25 of the extractor will engage the rim of the same.

The sear member 21 comprises a plate mounted on a pivot pin 31 passing through oppositely disposed webs on the bottom plate 1. In addition to the tooth 19 the member 21 has a cam finger 33 which, during the forward closing movement of the breech block, is arranged to be acted upon by the peripheral face of the breech block 9, as seen in Figure 4. At its upper rear corner the sear member is provided with a shoulder 35 for interengagement with a safety lever 37 (see Figures 1 and 2). The sear member has a laterally extending pin 39 secured thereon for engagement with one end of a torsion spring 41 which thereby serves to bias the member about its pivot 31 and urge the tooth 19 into the groove 17 in the limb of the breech block.

Also pivoted on the bottom plate 1 is a trigger 43 which at its upper end carries a pivoted trip pawl 45. The forward end of the trip pawl 45 is shoudered to engage a depending tail portion of the sear member 21 (see Figures 2, 3 and 4) and a coil spring 47 secured at one end to the rear of the pawl and at its other end to the bottom plate tends normally to maintain the pawl in engagement with the tail portion of the sear member.

The safety lever 37 is a forwardly extending member pivotally mounted at its rear end to the action body and spring-urged downwardly into contact with a cross pin 49 carried by a downwardly extending lug 51 on a thumb slide 53. The safety lever 37 has a sloping under-surface which is provided with two small forwardly and rearwardly spaced recesses 55 therein adapted to be engaged by the cross pin 49. When the thumb slide 53 is moved rearwardly the cross pin 49 lies in the rearward recess (as seen in Figure 2) so that the lever 37 is spring-urged downwardly to such a position that its forward end engages with the shoulder 35 on the sear member to prevent the latter from movement. Sliding of the thumb slide forwardly will cause the cross pin 49 to be engaged by the forward recess which moves and holds the forward end of the safety lever away from the shoulder on the sear member.

Cartridges are located in a tubular magazine 57 (Figure 2) formed in the butt of the firearm and are spring-urged forwardly into a dipper or feed tube 59 the forward end of which is located adjacent the firing chamber of the firearm. The feed tube 59 is provided with a downwardly projecting lug through which passes a pivot pin 61 located in oppositely disposed webs in the bottom plate 1. The feed tube 59 is acted upon by a second limb of the torsion spring 41 in such manner as normally to maintain it in alignment with the firing chamber but the forward end of the tube is located in the path of movement of the web 11 of the breech block 9.

Assuming the firearm to contain a charge of cartridges in its magazine and to be in uncocked position, the spring in the magazine will urge the

leading cartridge towards the firing chamber by pressure through the other cartridges. To cock the firearm the combined cocking handle and trigger guard 7 will be rocked forwardly about its pivot and a projection 63 thereon will engage the breech block and swing it rearwardly against the action of its torsion spring 15. As the breech block swings rearwardly a depression 65, formed in the periphery of the breech block 9, adjacent to the notch 17, will contact the forwardly extending cam finger 33 of the sear member 21 to allow the latter to be rocked slightly in a direction away from the safety lever to minimise danger of the sear member and the breech block becoming wedged together. As the breech block nears its cocked position the projection or tooth 19 on the sear member will drop into the notch 17 to maintain the breech block in cocked position. Depression of the trigger will thereafter cause the pawl 45 thereon to rock the sear member about its pivot 31 to free the breech block to the action of the spring 15 to allow the firing pin 29 to strike a cartridge and the extractor 23 to engage the case thereof. Upon discharge of the firearm, the breech block will be rocked rearwardly to cocked position once more. The pawl 45 is so arranged that even if the trigger is maintained in its depressed position the projection or tooth on the sear member will engage the notch in the breech block to maintain the latter cocked since if the pawl were to occupy its forward position the lower rear corner of the breech block would then, in recoiling, deflect the pawl downwardly somewhat against the action of its spring, to release the sear member and allow the tooth thereon to move into the notch in the breech block.

Having thus described our invention, what we claim as new and desire to secure by Letters Patent is:

1. A breech mechanism for a firearm, comprising a pivoted sector-shaped bifurcated breech block having a channel formed between the limbs thereof and an arcuate web connecting the limbs, a firing pin and cartridge extractor carried by the breech block, and a spring-actuated sear member for holding the breech block in a retracted position.

2. A breech mechanism for a firearm, comprising a pivoted sector-shaped bifurcated breech block having a notch in its periphery and a channel formed by the limbs thereof and having an arcuate web connecting the limbs, a firing pin and cartridge extractor disposed on said web and located rearwardly thereof relative to the breech chamber of the firearm, and a spring-actuated sear member cooperative with the breech block for holding the latter in a retracted position, said sear member comprising a plate having a projection engageable with the notch in the periphery of the breech block.

3. A breech mechanism for a firearm, comprising a pivoted sector-shaped bifurcated breech block having a channel formed by the limbs thereof and having an arcuate web connecting the limbs, a firing pin and cartridge extractor carried by the breech block, a spring-actuated sear member for holding the breech block in a retracted position, a movable trigger guard, and a projection on the trigger guard for retracting the breech block.

4. A breech mechanism for a firearm, comprising a pivoted sector-shaped bifurcated breech block having a notch in its periphery and a channel formed by the limbs thereof, and having an arcuate web connecting the limbs, a firing pin

and cartridge extractor carried by the breech block, a spring-actuated sear member cooperative with the breech block for holding the latter in a retracted position comprising a plate having a projection engageable in the notch in the periphery of the breech block, and trigger actuated means contacting said sear plate to move the projection thereon out of engagement with the notch in the periphery of the breech block.

5. A breech mechanism for a firearm, comprising a pivoted sector-shaped bifurcated breech block having a notch in its periphery and a channel formed between the limbs thereof and having an arcuate web connecting the limbs, a firing pin and cartridge extractor carried by the breech block, a spring-actuated sear member for holding the breech block in a retracted position, comprising a plate having a projection thereon engaging in the notch in the periphery of the breech block, a trigger, means contacting with said sear plate to move the projection thereon out of engagement with said notch upon actuation of the trigger, and means comprising a safety lever movable into contact with said sear plate to prevent movement thereof upon actuation of the trigger.

6. A breech mechanism for a firearm having a breech chamber, comprising a pivoted sector-shaped bifurcated breech block having a channel formed by the limbs thereof and having an ar-

20
25
30

cuate web connecting the limbs, a firing pin and cartridge extractor carried by the breech block, and a pivotally mounted tube lying between the limbs of the breech block to receive cartridges from a magazine and operative to feed the cartridges successively to the breech chamber.

7. A breech mechanism for a firearm having a breech chamber, comprising a pivoted sector-shaped bifurcated breech block having a channel formed between the limbs thereof and having an arcuate web connecting the limbs, a firing pin and cartridge extractor carried by the breech block, and a pivotally mounted cartridge feed tube lying between the limbs of the breech block, said tube being engageable by the arcuate web on retraction of the breech block and movable thereby away from the breech chamber.
